W. GARDNER.
GOVERNOR.

No. 8,151.

Patented June 10, 1851.

UNITED STATES PATENT OFFICE.

WM. GARDNER, OF NEW YORK, N. Y.

GOVERNOR.

Specification of Letters Patent No. 8,151, dated June 10, 1851.

To all whom it may concern:

Be it known that I, WM. GARDNER, of the city, county, and State of New York, have invented new and useful improvements in governors applicable to steam, gas, or water engines, and windmills or other machines propelled by similar powers and for different purposes where governors are used for regulating or producing uniformity in speed or supply and other desired effects; and I do hereby declare that the following is a full, clear, and exact description of the same, reference being had to the accompanying drawings, forming part of this specification, in which:

Figure 1, is an edge elevation. Fig. 2, is a side elevation with one of the sides or faces removed for the purpose of exhibiting the interior. Fig. 3, is a transverse, part 20 sectional, elevation. Fig. 4, is a detached view of mechanical arrangements operating the slide, and Fig. 5, is a part side view of the face removed in Fig. 2.

The same letters of reference denote similar parts in each of the several figures.

The nature of my invention relates to the production of the same effects as are now performed by the ordinary pendulum or centrifugal governor, and consists in hanging a pulley loosely on a counter shaft which the pulley drives by band or gear from the main shaft (or its equivalent) through the pressure of a spring or similar contrivance on an arm secured to the counter shaft, the 30 spring having its fulcrum fast to the pulley so that any tendency to acceleration or retardation of the pulley will, by its movement of "lead" or otherwise on the counter shaft, through racks and pinions, operate 35 the usual adjusting or regulating slide.

To enable others skilled in the art to make and use my invention, I will proceed more fully to describe its construction and operation.

45 A, is a hollow pulley driven by strap (as shown in red Fig. 2) from the main shaft of the prime mover, or it may be a toothed or friction wheel similarly operated.

B, is a counter shaft on which the pulley 50 A, is hung loose. Secured firmly to the counter shaft B, and situated within the pulley is a double arm C, which carries in one end of it a spindle D, positioned at right angles with the counter shaft and provided with pinions or part pinions E, F, the pinion E, working into a curved rack G,

attached to the inner surface of one of the pulley sides (or a similar arrangement may be applied to the periphery if preferred).

H, (Fig. 2) is a flat spring having its 60 fixed end secured in the rim of the pulley and acting against a fulcrum pin I, likewise attached to the pulley, the movable end of the spring pressing on the back of the double arm C, or any other suitable application of spring or pressure may be employed.

J, is the usual adjusting or regulating slide which moves on the shaft B, and is operated by a rack L, attached to it and 70 gearing into the pinion F.

The side of the pulley A, removed in Fig. 2 and shown in part in Fig. 5, has a curved notch or aperture M, in it for the travel 75 of the rack L, when operated on by the pinion F.

The shaft B, should have a fly wheel secured to it (as shown by dotted lines Fig. 1).

The operation in further description is as follows:

The pulley A, being set in motion by strap from the main shaft, or its equivalent, as described, and being made to travel in direction of the arrow Fig. 2, will cause the shaft B, also to revolve on which it sits loose, but is made to drive the shaft by the pressure of the spring H, on the arm C, the spring exerting a certain force thereon to overcome the impeding properties of the shaft B, and its attached fly, which force 80 will cause the pulley A, to be somewhat in "lead" of the shaft B, as compared with it when at rest and by the motion accomplishing this "lead" will operate, by the rack G, the pinion E, on the spindle D, turning likewise the pinion F, which will work outward the rack L, and with it the regulating slide J, that, at an assumed proper speed for the prime mover producing such result, is extended only so far as is necessary for the establishment of this velocity, and supposing the slide J, to be the usual slide operating the throttle valve of a steam engine by a forked arm or lever clasping the slide J, between its collars, and transmitting its motion in the ordinary way

(or if the governor be used for other contrivances or purposes its form and action is similar) then at this assumed speed, the slide J, will be at its proportionate position, 105 but if any undue irregularity in speed occur of the main shaft then will the pulley A,

reciprocate, or be proportionally affected, and if the irregularity be that of acceleration, the pulley A, will be driven further in "lead" of its shaft, and by this movement 5 through the racks and pinions as described will cause to be forced out the slide J, which by suitable mechanism will operate in closing the throttle valve; or if the irregularity be that of retardation, its action as 10 evident will be vice versa, the pressure of the spring H, on the arm C, being increased or diminished as the engine works faster or slower, and through the pulley A, being driven more or less in lead of its shaft, and 15 by the action of the racks and pinions as described, the adjusting slide J, is operated, and its effect communicated through any suitable agency to any desired purpose where the ordinary centrifugal governor is 20 employed. Also my improved form of governor may be adapted where the pendulum

or centrifugal governor is not admissible by reason of the necessity to maintain it in a strictly vertical position, while much room will be saved and economy in construction obtained.

What I claim as my invention and desire to secure by Letters Patent, is:

The employment of a loose wheel or pulley A, propelled by the prime mover, and driving its shaft B, through the action of a separate elastic force, weight or pressure, such as procured by the spring H, in combination with the several racks and pinions (or their equivalent) as described, for operating the adjusting or regulating slide J, substantially in the manner shown and specified and for the purposes set forth. 30 35

WILLIAM GARDNER.
